UNITED STATES PATENT OFFICE.

JOHN E. KNUCKEY, OF CHICAGO, ILLINOIS.

DESIGN FOR A ROPE-CLUTCH.

52,662.

Specification for Design. Patented Nov. 12, 1918.

Application filed April 8, 1918. Serial No. 227,381. Term of patent 7 years.

To all whom it may concern:

Be it known that I, JOHN E. KNUCKEY, a citizen of the United States, residing at Chicago, in the county of Cook and State of Illinois, have invented a new, original, and ornamental Design for Rope-Clutches, of which the following is a specification, reference being had to the accompanying drawing, forming part thereof.

The figure is a perspective view of a rope clutch illustrating my new design.

I claim:

The ornamental design for a rope clutch, as shown.

JOHN E. KNUCKEY.

Witnesses:

ARTHUR P. RANKIN,
EUGENE L. RACE.
